UNITED STATES PATENT OFFICE.

VALENTINE VON DER LIN AND SIMON JULIUS VON DER LIN, OF NEW YORK, N. Y.

FURNITURE-TREAD.

1,165,046.

Specification of Letters Patent. Patented Dec. 21, 1915.

Application filed December 12, 1914. Serial No. 876,772.

To all whom it may concern:

Be it known that we, VALENTINE VON DER LIN and SIMON J. VON DER LIN, citizens of the United States, and residents of the borough of Manhattan, city, county, and State of New York, have invented certain new and useful Improvements in Furniture-Treads, of which the following is a specification.

10 Our improvements relate to the furniture tread set forth in our concurrent application Serial No. 820,419, filed Feb. 24th, 1914, allowed August 25th, 1914, the distinctive feature of which structure is a base plate 15 adapted for attachment to a furniture support, a guide post on said base plate, an externally threaded tread member slidable on said guide post, interlocking means for preventing the rotation of said tread member on said guide post, and a nut sleeve 20 rotatably mounted on said base plate and engaging the threaded portion of the said tread member, for the purpose of affording a simple but effective adjustable tread for 25 application to the legs or supports of tables or other articles of furniture, whereby variations in length of support or inequalities of floor surface may be quickly and conveniently compensated for.

30 The present invention concerns more particularly the means employed for coupling the rotatable nut sleeve to the base plate, whereby the application of the device to a table leg or other furniture support is facilitated. It also includes the combination with the externally threaded tread member of means whereby the actual tread or contact surface may be changed or duplicated, all as hereinafter more fully set forth.

40 In the accompanying drawings, Figure 1, is an elevation of the lower part of the leg of a table or other article to which our adjustable tread is applied; Fig. 2, is a central vertical sectional elevation thereof; Fig. 3, 45 is a top view of the tread member; Fig. 4, a side elevation thereof; Fig. 5, a top view of the rotatable nut sleeve; Fig. 6, a section of the tread member, showing a removable bearing tip; Fig. 7, a sectional elevation 50 showing the use of a caster tread; Figs. 8, and 9, sectional details showing modifications in the means for securing the base plate to the furniture support.

55 The base or stud plate B, may be attached to a furniture leg or support L, by the use of any well known mechanical expedient, as

by the screw b, shown in Figs. 2, and 7, the screws b', b', shown in Fig. 9, or the socket b², shown in Fig. 8, according to the character or shape of the leg or other support to 60 which our adjustable tread is to be applied. The base plate B, consists essentially of an annular flange or disk from the lower side of which projects centrally the stud b^x, which performs the function of a guide post 65 and lateral support for the tread member T, the latter being formed with a central recess or socket t, the side walls of which embrace the sides of the stud b^x.

The body of the tread T, is cylindrical, 70 and is formed with the peripheral male thread t', for engagement with the female screw thread s, of the adjustable sleeve S. This adjustable sleeve S, is locked rotatably on the base plate B, by means of screws s', 75 s', mounted radially in the nut sleeve S, in such manner that they may be adjusted so as to cause their inner ends to protrude into the annular groove b³, formed in the peripheral edge of the base plate B. This peripheral annular groove b³, is preferably V shaped in cross section, and the ends of the screws s', s', are conical to correspond; and the design is to have the conical end of each screw fit snugly within the groove b³, when 80 the head of the screw is driven home against its seat in the sleeve S, without binding against the sides of the groove, so that the sleeve, while positively coupled to the base plate, will be free to rotate thereon. That 85 is to say, when the base B, is secured to the furniture support L, by means of the screw b, or equivalent mechanical expedient, the sleeve S, is rotatable upon the base plate B, 90 in either direction, to effect the desired adjustment of the tread T, with relation to the leg or support L, or to the floor or other sustaining surface. This is accomplished by reason of the engagement of the male thread t', on the tread T, with the female thread s, on the sleeve, but in order to effect 95 this result it is obvious that the sleeve S, alone must turn,—the tread member T, moving only longitudinally as related to the axis of the guide post b'. In other words 100 the sleeve S, and the base plate B, are coupled together by interlocking means which permit the rotation of the sleeve S,—the tread T, and the stud b', are coupled together by interlocking means which prevent 105 the rotation of the tread T, but permit of its being slid longitudinally on said guide 110 plate.

post b^x , in either direction to increase or diminish the extent of protrusion of the bearing surface t^2 , as related to the sleeve S, and hence as related to the leg or support L.

5 As stated in our concurrent application for patent hereinbefore referred to, this interlocking of the guide post b^x , with the tread T, may be effected in various ways, and we do not limit ourselves in this respect.

10 As shown herein the stud post b^x , is made rectangular in cross section, the socket t , in the tread T, being correspondingly formed. Whatever the interlocking means employed between the tread T, and the stud b^x , the result is the same in that the rotation of the tread T, upon said guide post b^x , is prevented while admitting of the adjustment of the tread member vertically in either direction within prescribed limits.

15 The adjustable nut sleeve S, is so formed peripherally as to facilitate its being turned axially on the base plate B,—a roughened surface s^x , being shown as provided for this purpose in the accompanying drawings.

20 It is obvious that the contact surfaces t^2 , of the tread T, may consist either of the lower portion of the tread itself, as in Figs. 1, 2 and 4, or of a caster roller as shown in Fig. 7, as may be found most expedient in adapting our device to various special uses and purposes, so that we do not restrict ourselves in this respect. In fact the tread T, may be provided with any form of caster bearing or contact, so that it is to be understood herein that by the term "tread" we mean to designate any floor or surface contacting device engaging with and controlled by the adjusting nut or sleeve S.

25 In this connection however we may state that an incidental feature of our present invention consists in providing the tread member T, with a detachable contact tip t^{22} , which when worn or damaged may be replaced by another. This bearing tip t^{22} , may be made of any desired or suitable material, as rubber vulcanized more or less, metal where necessary, or any substance or composition found most expedient for specific requirements and conditions of use.

30 The contact tip t^{22} , may obviously be detachably secured to the tread member T, by various mechanical expedients, a simple method being shown in which the lower side of the tread member T, is tapped with a

35 screw thread t^x , for the reception of the screw stud t^{23} , of the contact tip t^{22} , as shown in Fig. 6. This female tap t^x , may also be utilized for the attachment of a caster bearing as shown in Fig. 7.

40 By the use of the coupling screws s' , on the nut sleeve S, in conjunction with the

annular groove b^3 , in the base plate B, we are enabled to apply the tread device as a whole to a table leg or furniture support with convenience and facility. Thus by 65 turning back the screws s' , until their inner ends are withdrawn from the groove b^3 , the base plate B, may be withdrawn from the sleeve S, and tread member T, and screwed to the table leg L, or other support, 70 and the sleeve S, and tread T, then reapplied to the base plate, and secured thereto by turning the screws s' , inward until their heads rest against their seats in the sleeve S. This is a simple operation that may be 75 performed without the employment of especially skilled labor.

Providing the tread member with a detachable contact tip that may be replaced from time to time, as required, is also an 80 important practical advantage that adds materially to the life and utility of our adjustable tread device.

What we claim as our invention and desire to secure by Letters Patent is,

1. A furniture tread of the character designated comprising a base plate, formed with an annular groove, means for attaching said base plate to a furniture leg or support, a guide post on said base plate, an externally threaded tread member slidable on said guide post, interlocking means for preventing the rotation of said tread member on said guide post, and a nut rotatably mounted upon and attached to said base plate by means of screws engaging the walls of the aforesaid annular groove on said base plate and also formed with a screw thread engaging the threaded portion of the said tread member, for the purpose described.

2. A furniture tread of the character designated comprising a base plate formed with an annular groove, means for attaching said base plate to a furniture leg or support, a guide post on said base plate, an externally threaded tread member slidable on said guide post, interlocking means for preventing the rotation of said tread member on said guide post, and a nut rotatably mounted upon and attached to said base plate by means of protuberances engaging the aforesaid annular groove in said base plate and also formed with a screw thread engaging the threaded portion of said tread member, for the purpose described.
